GARMENT CLASP

Cora Braithwaite Battin, Avenel, N. J.

Application September 21, 1934, Serial No. 744,881

3 Claims. (Cl. 24—247)

This invention relates to new and useful improvements in garment clasps, and while it is capable of general use in connection with garment supporting devices, it particularly lends itself to use with garters for ladies' wear.

In garters for ladies' wear, it is highly desirable that the clasps employed be not visible beneath the outer garments and this is particularly true when the outer garments are formed from relatively thin materials as are evening clothes. Garment supporters and particularly hose supporters as generally constructed, do not accomplish this highly desirable result mainly for the reason that the adjusting and fastening clasps employed

10 are of bulky construction and cannot therefore, be successfully hidden beneath clothes and garments of the afore-mentioned type.

It is the object of the present invention to improve the construction of clasps for garments and so to construct them that when worn beneath garments of the thinnest material, they will not be apparent beneath the garment.

A feature of the present invention resides in a novel construction wherein the clasps employed

25 are relatively thin and flat, thereby creating no bulk.

Another feature of the invention resides in a novel construction whereby the clasps employed may be readily removed from and attached to the supporting member thus providing for complete removal of the clasps when it is desired to launder a garment to which the supporter may be attached.

Still another feature of the invention resides in a novel construction of garment clasp which provides for secure attachment to a garment and which, even when the garment is attached thereto is not bulky.

Other features of the invention will become apparent as the nature thereof is better understood and reference will therefore be had to the following specification and the accompanying drawing, wherein,

Figure 1 is a perspective view illustrating the manner of use of the present invention in connection with a hose supporter for ladies' wear,

Figure 2 is a plan view of the garment clasp, a portion of the garter or supporting member being shown,

Figure 3 is a longitudinal sectional view on an enlarged scale, taken substantially on the line 3—3 of Figure 2,

Figure 4 is a detail sectional view illustrating the manner in which the clasp is attached to a garment such for example as a stocking,

Figure 5 is a detail fragmentary plan view of the clasp, a portion of the garter being broken away.

Figure 6 is a perspective view of the clasp with the garter removed,

Figure 7 is a plan view of a slightly modified form of the invention,

Figure 8 is a longitudinal sectional view, taken on the line 8—8 of Figure 7,

Figure 9 is a plan view of the modified form of the invention illustrated in Figure 8; and,

Figure 10 is a transverse sectional view illustrating a still further modified form of the invention.

Referring to Figures 1 to 6, inclusive, of the drawing, the clasp comprises a rigid frame-like member 15 which is bridged by a transversely extending bar 16, the forward edge of which is provided with a series of biting teeth 17. Extending inwardly from the ends of the rigid frame and overlying a portion of the same there are two tongue-like members 17', which preferably have rounded edges 18 as shown.

The garter is designated 19 and on one end it has a clip of metal designated 20. In attaching the rigid frame member to the garter, the end of the garter provided with the clip is inserted in a slotted opening 21 formed in the rigid frame. The metal clip 20 will then engage the portion 22 of the rigid frame and the garter material is then looped over the upper rear edge of the rigid frame, as designated at 25 in Figure 3. The garter 19 is next threaded through the space 26 between the forward edge of the rigid frame and the teeth 17 of the toothed bar 16 as indicated at 28 in Figure 3, after which the garter 19 is passed beneath the tongue-like members 17', as shown in said Figure 3. In this position the teeth 17 will bite into the garter 19 and prevent movement of the clasp relative to the garter to hold the same in adjusted position. To adjust the garter it is only necessary to grasp the portion 29 thereof and pull the same downwardly in Figure 3 to shorten the garter or upwardly to lengthen the garter, it being understood that when the portion 29 is moved upwardly it will be held out of engagement with the teeth 17 and allowed to move into engagement with the teeth 17 after the proper adjustment has been made.

Garter attaching means is provided and this means consists of a loop 30 which is pivotally attached to the frame 15 heretofore mentioned. To pivotally attach the loop 30, frame eyes 31 are provided upon the forward edge thereof and the free ends of the loop are bent at right angles to

the loop and received within said eyes. The loop 30 has an enlarged portion 32 between its ends, the purpose of which will be hereinafter described.

5 Pivots connected to the frame 15 in eyes 33 which are between the eyes 31, there is a rigid member 34, which is herein illustrated as formed of two strands 35 of rigid wire. This rigid member is adapted to swing through the loop 30 to 10 either the front or rear thereof. Carried by the rigid member 34 and adapted for movement from front to rear of the loop 30 with said rigid member, there is a relatively thin disk-like member 36. This member has an eye 37 by which it may be 15 slidably mounted upon the rigid member 34 and is adapted also for rotary movement about the axis of rigid member 34 in order that it may be turned on edge, or slightly tilted to pass through the enlarged portion 32 of the loop 30 as the rigid 20 frame 34 swings from front to rear of the loop 30.

In attaching the device to the garment, the rigid member 34 together with the member 36 are swung upwardly and the garment, which is designated 40, is placed over the loop 30. With 25 the parts in this position, the member 36 is moved downwardly into engagement with the garment, which in the present instance is shown as a stocking, slightly tilted and passed through the enlarged portion 32 of the loop 30. After it has been 30 passed through the enlarged portion 32 of the loop 30, the member 36 is moved forwardly along the rigid member 34 until it is out of alignment with the enlarged portion 32 of the loop, whereupon the garment will be gripped between the loop and the 35 member 36, as best illustrated in Figure 4. When it is desired to detach the clasp from the garment, it is only necessary to grasp the member 36 and move it rearwardly along the loop until it can be tilted through the loop, whereupon the garment 40 becomes immediately detached.

In Figures 7 to 9, inclusive, I have shown the garment attaching portion of the clasp applied to an ordinary rigid frame-like buckle, as distinguished from the specially designed frame-like 45 buckle heretofore described. In these figures the garter, which is designated 41, is threaded through the space 42 of the frame-like buckle 43, over the bridging bar 44 and through the space 45. The bar 44 is provided with teeth 46 which bite into the 50 garter 41 and prevent movement of the buckle along the garter.

In Figure 10, I have shown a modified form in which the buckle is formed from a single piece of material folded upon itself as at 50, to provide 55 two parallel members 51 and 52. In this form the eyes 53 in which the loop 30 is mounted and the eyes 54 in which the rigid member 34 is to be mounted, are formed by cutting away a portion of the two members 51 and 52 at their line or point 60 of fold. In this form of the invention, the eyes 53 and 54 are so constructed that half of each of its eyes will be at opposite sides of a center line drawn through the buckle, and the resulting garment clasp will be relatively thin and less bulky 65 than where the eyes are formed as heretofore described.

From the foregoing it will be apparent that the present invention provides a new and improved

form of garment clasp which especially lends itself for use in connection with hose supporters for wear beneath garments of relatively thin and light materials, since the garment clasp is of such relatively flat and thin construction that it forms 5 no bulk beneath the said garments, and therefore, is not apparent when in use.

Furthermore, the relatively thin disk-like member 36 employed together with the loop 30 as described, provides an effective holding means for 10 the garment without creating noticeable bulk when worn beneath garments of relatively thin light material.

While the invention has been herein disclosed in its preferred form it is to be understood that 15 it is not to be limited to the specific construction shown and that it may be practiced in other forms without departing from the spirit thereof.

Having thus described the invention, what is 20 claimed as new, is:

1. A garment clasp comprising a pair of clasping members, one of said members being of button loop formation and the other of said members being of elongated construction, means for pivotally attaching said members at one end for independent movement, said elongated member being swingable through the loop, and a button 25 slidably carried by the elongated member and rotatable about the elongated axis thereof for movement through the loop together with a portion of the garment to be clasped to selectively position the head of the button at opposite sides of the frame in cooperating clasping engagement therewith. 30

2. A garment clasp comprising a pair of clasping members, one of said members being of substantially U-shaped formation having a portion intermediate its ends formed into a loop, the other of said members being of substantially V-shaped formation, means for pivotally attaching said 40 members at one end for independent movement, said V-shaped member being swingable through the U-shaped member and a button slidably carried by the V-shaped member and rotatable about the elongated axis thereof for movement through 45 the loop together with a portion of the garment to be clasped to selectively position the head of the button at opposite sides of the U-shaped member in cooperating clasping engagement therewith, the inclined sides of the V-shaped 50 member normally maintaining the button in position out of alignment with the loop to prevent accidental withdrawal thereof. 55

3. A garment clasp comprising an outer elongated garment clasping member of button loop 55 formation, an inner elongated member, attaching means for said members pivotally connecting the same for independent movement, said inner member being swingable through the outer member into a position at opposite sides thereof, and a 60 button including a shank having an eye for receiving the inner member, said button being slideable on the inner member and rotatable about the elongated axis thereof and movable through the loop together with the inner member to selectively clasp a garment at either side of the outer member. 65
